UNITED STATES PATENT OFFICE.

OGDEN P. LETCHWORTH, OF BUFFALO, NEW YORK.

HALTER-TRIMMING.

SPECIFICATION forming part of Letters Patent No. 272,715, dated February 20, 1883.

Application filed December 12, 1882. (No model.)

To all whom it may concern:

Be it known that I, OGDEN P. LETCHWORTH, of the city of Buffalo, in the county of Erie and State of New York, have invented new and useful Improvements in Halter-Trimming, of which the following is a specification.

This invention relates more particularly to an improvement in that class of halter-trimmings which are employed for connecting the chin-strap with the cheek-straps, and has for its object to so construct the trimming that a bit can be readily connected therewith, thereby enabling the halter to be used as a bridle when desired.

My invention consists of the peculiar construction of the halter-trimming, which will be hereinafter fully described, and pointed out in the claim.

In the accompanying drawings, Figure 1 is a perspective view of a halter provided with my improvement. Fig. 2 is an inside elevation of the trimming on an enlarged scale. Fig. 3 is a side elevation thereof at right angles to Fig. 2. Fig. 4 is a vertical section in line *xx*, Fig. 2.

Like letters of reference refer to like parts in the several figures.

A represents the chin or lower strap of the halter, B B the cheek-strap, C the crown-strap, and D the throat-latch, all arranged and constructed in any suitable and well-known manner.

E represents the metallic trimmings whereby the lower ends of the cheek-straps B B are secured to the chin-strap A. The trimmings represented in the drawings consist of a plate, *f*, which is provided at its sides with two loops, *f' f'*, through which the chin-strap passes, and at its top with a loop, *f²*, through which the cheek-strap passes. Both the chin-strap and

cheek-strap are secured to the plate *f* of the trimmings by a rivet, *g*.

H represents a snap-hook, which extends downwardly from the trimming, and which is cast in one piece therewith. The shank and body of the snap-hook form a downward extension of the plate *f* of the trimming.

h represents the spring of the snap-hook, which is preferably arranged on the inner side of the hook, so that the trimming is substantially straight on its inner side, while the body of the hook projects outwardly.

i represents a bit of any suitable and well-known construction, and *jj* represent the rings at the ends of the bit. These rings can be readily engaged with the snap-hooks H on the trimmings E, as represented in Fig. 1, whereby the halter is adapted to be used as a bridle, and the bit is as readily detached from the halter when the latter is to be used for the ordinary purposes of a halter.

The snap-hooks H do not interfere with the ordinary use of the halter, and do not materially impair or affect the appearance of the halter when the bit is detached therefrom.

I am aware that it has been common to provide strap attachments with integral snap-hooks; also, that bridle-bits have been provided at their ends with snap-hooks adapted to interlock with the bridle-trimming, and these constructions I do not claim; but

I claim as my invention—

A halter-trimming provided with loops *f' f²*, for the reception of the chin and cheek straps, and a snap-hook, H, cast in one piece with the trimming, substantially as set forth.

OGDEN P. LETCHWORTH.
